[57] CLAIM

The ornamental design for a combined cleaning implement handle and interchangeable heads therefor, as shown and described.

DESCRIPTION

FIG. 1 is a perspective view of a combined cleaning implement handle and interchangeable heads therefor, showing my new design and shown with a round brush;
 FIG. 2 is a bottom perspective view thereof;
 FIG. 3 is a top plan view thereof;
 FIG. 4 is a front perspective view thereof;
 FIG. 5 is a side elevational view, the opposite side being a mirror image thereof;
 FIG. 6 is a perspective view of a combined cleaning implement handle and interchangeable heads therefor, shown with a rectangular brush;
 FIG. 7 is a bottom perspective view thereof;
 FIG. 8 is a top plan view thereof;
 FIG. 9 is a front perspective view thereof;
 FIG. 10 is a side elevational view, the opposite side being a mirror image thereof;
 FIG. 11 is a perspective view of a combined cleaning implement handle and interchangeable heads therefor, shown with a square sponge;
 FIG. 12 is a bottom perspective view thereof;
 FIG. 13 is a top plan view thereof;
 FIG. 14 is a front perspective view thereof;
 FIG. 15 is a side elevational view, the opposite side being a mirror image thereof.
